WINDOW OPERATOR

Anton Rappi, Buffalo, N. Y., assignor to Trico Products Corporation, Buffalo, N. Y.

Application November 5, 1940, Serial No. 364,421

14 Claims. (Cl. 268—125)

This invention relates to a power operated mechanism for the automatic opening and closing of closures or windows, such as motor vehicle windows, wherein a motor of either the fluid or the electric type, is utilized to regulate the window. In window mechanisms of this type when the power goes off or is interrupted it is impossible to move the window from an extreme position, and consequently an emergency arises which is not easily dealt with.

An object of the present invention is to provide a power operated window or closure mechanism with means by which the source of power when dead or ineffective may be readily disconnected and the window freed or disposed for manual actuation.

A further important object of the invention is to provide a mechanism which when the source of power is disconnected will move the window from an extreme position in which the free edge of the window is inaccessible to a position which will permit the edge of the window being readily engaged by the hand to facilitate manual movement of the window to the opposite extreme position, more or less.

In the drawings

Fig. 1 is a fragmentary phantom view of a motor vehicle embodying the present invention;

Fig. 2 is an irregular section through the operating mechanism depicting more clearly the window freeing release;

Fig. 3 is a detailed sectional view through the window opening spring;

Fig. 4 is an exploded view in perspective of parts of the transmission; and

Fig. 5 is an enlarged sectional view through the motor piston.

Referring more particularly to the drawings, the numeral 1 designates a window, which term is used herein to include doors and like closures. The illustrated closure is the side window of a motor vehicle, which is slidable vertically in guideways 2 for opening and closing adjustment. The mechanism for so adjusting the window embodies a lifting arm 3 and a power arm 4, both pivotally mounted on a common axis 5 and constituting, when locked together, a bell crank lever which is rocked by a motor generally indicated at 6. This motor may be of any desired type, that illustrated being of the fluid type and consisting of a chamber 7 and a piston 8, the latter being connected by a rod 9 to the power arm 4. A counterbalance spring 10 of convolute form is anchored on the pivot pin or shaft 5 and has its free end connected to the lift arm 3 so

as to counterbalance the weight of the window 1.

The two arms of the bell crank lever are detachably locked together in a manner enabling ready disconnection when it is desired to release or free the window from the motor, such as when the motor is dead and it is desired to open or close the window. According to the illustrated embodiment one of the levers is provided with a quadrant-like extension 11 having a keeper notch or seat 12 while the companion arm is provided with an angular, extension 13 turned down at its outer end to provide a guide flange 14 overhanging the concentric margin of the quadrant extension 11. The extension 13 is provided with a bearing or opening 15 adapted to register with the notch 12. A lock bolt or pin 16 is slidable in this bearing 15 and is projected into and retracted from the keeper notch by suitable means such as the plate 17 to which it may be connected. This lock plate may be of spring stock and secured to the extension 13 by means of the rivets 18, or it may be otherwise mounted for the bolt imparting movement. A stop shoulder 19 on the quadrant 11 is engageable by the guide flange 14 to limit relative movement between the arms in one direction and to determine the point of registry between the bolt and its keeper notch. A spring 19 may bear on the outer side of the lock plate to urge the lock bolt to its operative position, the spring being held in place by a retaining pin 20. The lock plate overhangs the extension 13 to an extent sufficient to overlie a releasing button 21 which is spring retracted and adapted to be manually depressed to lift the lock plate and thereby disengage the lock pin from the keeper notch 12. The lock plate is sufficiently wide to be operatively related to the release button in all positions of the window.

In the sliding window of the present day automobile the upper edge is received in a groove or seat in the window frame and when the window is closed this edge is embedded making it inaccessible. Therefore, if the motor should be dead and it is desired to open the window the motorist is handicapped by not being able to accomplish this in a ready manner. With the release mechanism just described it is possible to grasp the window on opposite sides between the palms of the hands and push it downwardly since the window itself is freed from the motor.

To facilitate this manual opening of the window means are provided to mechanically move the same automatically to a partially opened position for exposing its upper edge sufficiently to

enable the motorist inserting his hand in the window opening and over the upper edge whereby he may quickly move the window downwardly to a fully opened position. This may be accomplished by a power means which is normally dormant or inactive and is herein depicted as comprising a spring motor having a spring 22.

A link 23 is pivoted at 24 on one of the arms and has its opposite end portion slidably in a yoke 25 pivoted on the companion arm. The slidably end of the arm protrudes through the yoke and carries the spring 22 between a head 26 and a washer 27. Beneath the washer 27 the link is provided with a shoulder 28 adapted to be withdrawn into the yoke 25 when the arms 3 and 4 are moved into their locked relationship at which time the washer 27 will seat against the yoke and compress the spring, holding the same under compression ready to act when the release is again actuated. The washer 27 is free to move until arrested by the shoulder 28, the extent of movement being sufficient to partially open the window the desired distance. Further expansion of the spring is prevented by the shoulder 28 as the link is projected further through the yoke during the subsequent manual opening movement of the window, the link merely sliding in the yoke as the arms 3 and 4 move relative to each other. When the lock is operative the spring 22 is inactive with respect to the window, remaining dormant but ready for opening the window when next released.

When the release is effected the spring will move the lift arm downwardly to open the window a slight distance, such as one or two inches, sufficiently to enable the insertion of the fingers over the upper edge of the glass. The window may then be easily moved manually to its fully opened position free and independent of the motor. When the button 21 is released the pin 18 will merely ride on the face of the quadrant extension 11, and when the motor is next placed in operation and brings the lock pin into registry with the keeper notch 12 the spring lock plate 17, herein supplemented by the spring 19, will re-lock the two arms together against the action of the spring 22.

The power transmitting connection between the motor and the window will obviously depend upon the type of motor employed and preferably involve means to prevent the unauthorized opening of the window from the outside. In the electric drive a worm gearing may be used for this purpose but in the more simplified fluid drive illustrated a clutch or brake is incorporated in the piston construction, as set forth more fully in application Serial No. 347,941, filed by me jointly with Erwin C. Horton. This is generally illustrated in Fig. 5, wherein the piston has a section 30 fixed on the piston rod 9 and a floating section 31 which is movable relative thereto. The brake shoes 29 are interposed between the fixed and floating piston sections and have cam surfaces 32 opposing cam surfaces 33 on the hub of the fixed section. Rollers 34 ride on and between the cooperating cam surfaces to expand the shoes against the chamber wall when an outward pull is exerted on the piston rod as would be the case when an attempt is made to pry open the window. However, fluid actuation of either piston section will merely cause the brake to idle. For example, fluid pressure acting on the fixed piston section will pull inwardly on the piston rod while fluid motion of the floating section 31 will act through the rollers and push the rod

outwardly. This braking construction does not, however, prevent the movement of the piston rod in the opposite direction by any force applied to the window for closing the same.

5 In this connection it will be observed that upon depressing the release button 21 to disengage the lock bolt from its keeper recess, should the window be frozen or otherwise jammed in a closed position so that the opening spring 22 would be unable to overcome the abnormal resistance offered, the said spring will nevertheless act upon the power arm 4 and move the piston inwardly a slight distance by reason of the clearance at the end of the piston chamber and this clearance 10 will be sufficient to bring the recess out of registry with the bolt so that the motorist may then release the button 21 and the bolt will merely ride upon the side face of the quadrant 11. With the arms 3 and 4 thus disconnected the window 15 may be grasped between the palms of the hands and effort placed upon the window to overcome 20 such abnormal resistance.

From the foregoing it will be observed that the window or closure operating mechanism will be 25 automatic in its operation in the usual manner, the power being transmitted from the motor through the rigid bell crank to open and close the window, as desired. Should the engine be turned off or, if for any other reason the motor 30 should fail and it is desired to open the window the release button 21 is pushed to disengage the parts 3 and 4 from the transmission whereupon 35 the spring 22 will function to partially open the window and thereafter the hand may be placed over the upper edge of the window to pull the window down to its more or less fully opened position. This is accomplished without the drag 40 of the motor since the window is free and disconnected therefrom. When the motor is again placed in operation the parts 3 and 4 will be automatically coupled.

In the illustrated embodiment the motor is 45 adapted for operation by suction or subatmospheric pressure, such as that developed in the intake manifold of the motor vehicle engine. Suction is preferably applied to both sides of the piston simultaneously by means of the conduits 34 and 35 which are equipped with venting control valves 36 and 37. When either valve is 50 opened the corresponding end of the chamber 7 will be vented to the atmosphere and thereby provide the required pressure differential for the actuation of the piston.

Certain windows of the modern car, such as 55 the front side windows, are fully received within the window wells of the vehicle doors. Consequently, by a reversal of the foregoing arrangement the invention may be employed to project the upper edge of the glass from the well to permit 60 the manual lifting of the window when the motor is dead.

While the foregoing description has been given 65 in detail, it is merely illustrative of the inventive principles involved which may be applied to other physical embodiments without departing from the scope and spirit of the invention claimed.

I claim:

1. Window operating mechanism including a 70 window lifting member operable to slide a connected window vertically, a power member detachably connected to the lifting member, a motor operatively connected to the power member, a spring connecting the two members under tension and operable to impart window actuating movement to the lifting member independ-

ently of the other when the two members are detached from each other, and means for detaching the lifting member from the power member.

2. Window operating mechanism including a window lifting member operable to slide a connected window vertically, a power member, a lock means carried by one member and detachably engaged in a keeper recess in the other member to detachably connect the two members, a motor operatively connected to the power member, a spring connecting the two members under tension and operable to rotate the lifting member and thereby actuate a connected window when the members are detached from each other, said members being mounted on a common axis for pivoting, and a manually operable member for disengaging the lock means from the recess to free the window from the motor.

3. A window having an arm connected at one end thereto, means pivotally mounting the arm at the opposite end, a power arm pivotally mounted coaxially adjacent the first arm, means detachably coupling the two arms for movement in unison in the manner of a bell crank, a spring connecting the two arms to impart movement to the first arm relative to the second arm when uncoupled therefrom, and the power means operatively connected to the power arm for moving the same to actuate the window, said coupling means acting when operative to render the spring inoperative.

4. In a closure operating mechanism, a bell crank lever having relatively movable arm parts with means detachably connecting the parts for movement as a bell crank unit, counter-balance means for the unit acting to counterbalance the closure to which one of the arm parts is connectible, a drive operatively connected to the companion arm part and embodying means to lock the latter against closure imparted movement of said companion arm part, and means normally restrained by said connecting means against exerting any counteracting force on the counterbalance means, said restrained means acting on the closure arm part upon disconnection of the arm parts by said connecting means for moving said closure arm part a predetermined distance to effect movement of the closure independently of the locked companion arm part.

5. A motor vehicle having a window, a motor for adjusting the window from a closed position, transmission means operatively and detachably connecting the motor to the window, manual means for disconnecting the window from the motor when the latter is dead whereby the window is free to be moved independently of the motor, and auxiliary means normally inoperative during motor adjustment of the window and automatically operable by and upon such disconnection to move the window to a predetermined opened position short of its fully opened position.

6. Window operating mechanism including a window lifting member operable to actuate a connected window, a power member detachably connected to the lifting member and operatively connectible to a motor, a spring connecting the two members under tension and operable to impart window actuating movement to the lifting member independently of the other when the two members are detached from each other, said spring being normally inactive and movable with the two members as a unit, and means for de-

taching the lifting member from the power member to permit the spring to function.

7. Window operating mechanism comprising a window connected member, a motor, transmission means operatively connecting the member to the motor for actuating the same to open an engaged window, manually controlled means for rendering the transmission means inoperative to free the member from the motor, and a second motor wholly carried by said member and transmission means and operable to move the member when freed to a window opened position, said second motor being normally restrained by said second means and automatically effective upon the freeing of said member by said second means.

8. A window operator comprising a motor, transmission means operatively connecting the motor to a window for moving the same, means for controlling the operation of the motor, means manually operable to disrupt the transmission means to free the window from the motor for manual movement when the motor is dead, and a second motor connected to the window and normally inoperative thereon but automatically operable by and upon the disruption of the transmission means by the manual means whereby to dispose the window in other than a fully closed position to enable such manual movement.

9. Window operating mechanism comprising, in combination with a window, a motor, transmission means operatively connecting the motor to the window and including means for locking the window shut, said transmission means including a unit comprising relatively movable parts and means normally acting to hold said parts against relative movement, means operable to render said holding means inoperative, and means normally restrained by said holding means from exerting any counteracting force on the motor and automatically operable when said holding means is inoperative for effecting relative movement between said parts in disregard to said locking means to move the window from one limit of its movement, wherein it is inaccessible, to a position accessible for manual operation.

10. Window operating mechanism comprising, in combination with a window, a motor, transmission means operatively connecting the motor to the window and including means for locking the window shut, manually controlled means operable to render the lock ineffective on the window to permit manual opening movement of the latter, and normally restrained means releasable by said manually controlled means to concurrently effect an opening of the window to an accessible position independently of the motor for being manually grasped.

11. Window operating mechanism comprising, in combination with a window, a drive, a power transmission operatively connecting the drive to the window, a clutch operable for locking the window, emergency means operable to render the clutch ineffective on the window to free the latter and thereby enable the window being manipulated manually although the clutch is locked, and means normally restrained by said first means and releasable thereby to open the window upon the freeing of the latter by said first means, the normally restrained means being unaffected by the drive operation of the window.

12. In a window regulator and particularly a power operated regulator, the combination of a window regulator mechanism, including the

parts at the load end of the mechanism and the parts at the power end of the mechanism, a clutch operating to be released by the operation of the power parts of the regulator mechanism to lock the window in position, a releasable connection for tying the power parts to the load parts to permit movement of the window in an emergency although the clutch is locked, and means normally ineffective on the window and operable by and upon rendering said releasable connection inoperative to open the window upon the untying of the power parts from the load parts by said releasable connection.

13. In a window regulator and particularly one of the power operated type, the combination of a load arm, a power arm, the two pivoted on the same axis but having a connection between each other which can be released, a clutch for normally locking the power arm and load arm

5 against movement by effort originating in the load arm, means for rendering the clutch inoperative, and means normally restrained by said releasable connection and operable to open the window when the releasable connection is actuated to disconnect one arm from the other.

14. In a motor vehicle, a window, a motor, means operatively connecting the motor to the window for opening and closing the same and including a clutch for locking the window closed, manual means operable to render the clutch ineffective on the window to free the latter whereby the window may be manually operated although the clutch is locked, and means normally ineffective upon the window and releasable to open the window by and during the operation of said manual means.

ANTON RAPPL.
